UNITED STATES PATENT OFFICE.

JOSEPH W. HOBSON, JR., OF BAYONNE, NEW JERSEY.

FOUNTAIN-PEN.

1,159,027.

Specification of Letters Patent.

Patented Nov. 2, 1915.

Application filed April 30, 1915. Serial No. 25,004.

To all whom it may concern:

Be it known that I, JOSEPH W. HOBSON, Jr., a citizen of the United States, residing at Bayonne, in the county of Hudson and State of New Jersey, have invented new and useful Improvements in Fountain-Pens, of which the following is a specification.

This invention relates generally to fountain pens, and particularly to a new and novel form of feed bar therefor.

The object of this invention is to provide in a feed bar, means for retaining at or in the vicinity of the delivery end thereof, the surplus or extra supply of ink that projects itself to the point of discharge, faster than can be accommodated previous to, during or after the act or process of writing, and to automatically, by gravitation or capillary attraction, hold in suspense the before mentioned surplus or extra supply of ink which might ordinarily drop or flood at the point of the writing nib, or flow faster than necessary during the act or process of writing.

This invention also provides, by reason 25 of its structure, construction or principle of action, a method or means of furnishing a sufficient, regulated supply of ink to the pen nib during the act or process of writing. This object is accomplished by providing a 30 feed bar of a general shape or contour and having an ink channel disposed longitudinally thereof. The improvement in the art resides in the provision in the bar and at the opposite sides of the said channel, of ink 35 storing pockets of a shape and design calculated to receive necessary or surplus quantities of ink and supply the same in a proper draft or manner to the nib when in use for writing, and to prevent dropping or flooding 40 of ink at end of said nib.

In the accompanying drawing:—Figure 1 is a side elevation of a pen with parts in section showing the feed bar in position therein. Fig. 2 is a plan view of the feed 45 bar with part broken away. Fig. 3 is a perspective view of the feed bar.

As illustrated in the accompanying drawing the feed bar 1 is of a general shape or configuration and is provided at its upper 50 side portion with a longitudinally disposed channel 2. The lower end of the channel 2 terminates short of the lower end of the feed bar 1, but the upper end of the said channel 2 extends through the upper ex-

tremity of the said bar. Pockets 3 are provided at the opposite sides of the bar 1 and they lie along line 5 below the channel 2. The bottoms of pockets 3 are sloped and are preferably concaved, as indicated by 4, and the said pockets 3 extend along the 60 lower portion of the bar 1 as best indicated in Figs. 1 and 3 of the drawing. The pockets 3 are disposed with their long dimensions parallel with the axis of the bar 1, and the opposite side walls of the said 65 pockets 3 are approximately radially disposed with relation to the axis of the bar 1. Throats 5 are provided at the opposite side 70 portions of the bar 1 in the vicinity of the lower end thereof. The throats 5 communicate at their upper ends with the lower ends of the pockets 3, but the lower ends of the throats 5 terminate short of the lower end of the feed bar 1.

The long dimensions of the throats 5 are 75 disposed approximately at an acute angle with relation to each other and the said long dimensions of the said throats converge toward each other in a downward direction toward the lower end of the bar 1. The 80 lower ends of the throats 5 and the lower end of the channel 2 terminate at approximately the same line extending transversely across the lower end of the bar 1.

The operation of the feed bar is as follows: When the nib (not shown) is applied to the bar 1 in the usual manner, and the pen is brought to a semi-upright position for writing, the ink flows from the reservoir in the barrel of the pen down 85 through the channel 2 until it arrives at the lower end of the said channel. The ink then travels along the inner surface of the nib by capillary attraction and the surplus enters the throats 5, passing up along 90 the said throats and entering the pockets 3 where it is stored. Thus, when the nib is placed upon paper or other material for writing, there is an ample supply of ink in the vicinity of the pointed end of the nib 100 for writing purposes but the said surplus supply is held in check, preventing the same from flowing too fast, and dropping or flooding at the end of the pen nib. In other words, the ink is supplied to the 105 pointed end portion of the nib in the form of a thin film, of ample volume for ordinary writing needs. The ends of throats 5 join.

ing the points of pockets 3 form a check-dam which prevents undue weight-pressure on ink held in suspension in throat 5.

Having described the invention what is claimed is:—

1. A feed bar having a channel and provided at its opposite sides with pockets, the inner walls of which are sloped, the long dimensions of the pockets being parallel with the long dimensions of the channel, said bar also having throats leading from the vicinity of the lower end of the bar into the lower end of the said pockets, the lower ends of the throats being spaced from the channel and the long dimensions of the throats converging toward each other and toward the channel.
2. A feed bar having a channel and provided at its opposite sides with pockets disposed with their long dimensions parallel with the axis of the bar, said pockets having their opposite side walls approximately radially disposed with relation to the axis of the bar and throats communicating with the lower ends of the pockets and having their long dimensions converging in a downward direction toward each other.

25

3. A feed bar having a channel and provided at its opposite sides with pockets, said bar also having throats extending from the vicinity of its lower end into the lower ends of the pockets, the said throats at their points of merger in the pockets being contracted.

30

In testimony whereof I, affix my signature in presence of two witnesses.

JOSEPH W. HOBSON, JR.
